CLAIM

We claim the ornamental design for a spray bottle assembly, as shown and described.

DESCRIPTION

FIG. 1 is a front perspective view of showing our new design for a spray bottle;

FIG. 2 is a back perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included for the purpose of illustrating the portions of the spray bottle assembly that form no part of claim design.

1 Claim, 7 Drawing Sheets
